[57] CLAIM

The ornamental design for a baseball cap or the like, substantially as shown and described.

DESCRIPTION

FIG. 1 is a top plan view of a baseball cap or the like showing my new design;

FIG. 2 is a right side elevational view as seen when worn, the opposite side being a mirror image thereof;

FIG. 3 is a front elevational view thereof;

FIG. 4 is a rear elevational view thereof;

FIG. 5 is a bottom plan view thereof;

FIG. 6 is a top plan view of a modified form of the baseball cap shown in FIG. 1;

FIG. 7 is a right side elevational view as seen when worn, the opposite side being a mirror image thereof;

FIG. 8 is a front elevational view thereof;

FIG. 9 is a rear elevational view thereof; and

FIG. 10 is a bottom plan view thereof.
